[57] ABSTRACT

This invention relates to a circuit which substantially eliminates current flow through the deflection coils of a cathode ray tube (CRT) when the CRT beam is not being moved through a raster pattern. The circuit includes a time out circuit which generates a predetermined signal at all times except for a predetermined time period after it receives an input. When the beam is being moved through a raster pattern, successive pulses are applied as inputs to the time out circuit, the time period between the pulses being less than the predetermined time period. There is also a control circuit provided for each deflection coil which control circuit includes a means responsive to a signal from the time out means for causing the control circuit to apply zero current to the corresponding deflection coil.

**CIRCUIT FOR ELIMINATING CURRENT FLOW
THROUGH THE DEFLECTION COILS OF A CRT
WHEN THE BEAM IS NOT BEING MOVED
THROUGH A RASTER PATTERN**

This invention relates to a circuit for use in a cathode ray tube (CRT) display device which circuit substantially eliminates current flow through the deflection coils of the CRT when the CRT beam is not being moved through a raster pattern.

BACKGROUND OF THE INVENTION

In order to maintain the display of information on a CRT, it is necessary that the CRT display be periodically refreshed. In other words, once every n milliseconds (where n is a function of the refresh rate of the CRT) the CRT beam traces a predetermined pattern across the face of the CRT screen with the beam being selectively intensified under control of information inputs to rewrite the displayed information on the screen. Typically, the refresh rate is roughly 60Hz (i.e., 60 times a second) resulting in a frame period of roughly 16.67 ms. However, particularly for small tubes, the time required to write a frame of data is substantially less than the frame period. Thus, with a five inch display tube, only a 6.25 ms time slot might be required to refresh the display leaving roughly a 10.42 ms time period when no data or raster are present.

In existing systems, the deflection coils are either left energized to position the CRT beam at the end-of-raster position of the beam during this no-data period, or the deflection coils are energized to return the beam to its start-of-frame position. In either event, the beam is not intensified during this period to prevent damage to the tube phosphor. However, the deflection coils are energized during this period, causing the coils to draw unneeded power. More important, the current flowing through the coils heats both the coils and the other components connected in the deflection coil circuits, including components of the output stages. This heat reduces the life of the coils and of the other components and thus increases maintenance costs and reduces reliability for the display device. In order to at least partially compensate for the adverse effects of this additional heat, additional costs must be incurred in providing heat dissipating members.

In recognition of the above, some efforts have heretofore been made to reduce or eliminate the current flow through the deflection coils during the no-data periods of each frame. However, these efforts have either been both complicated and expensive, or have been only partially effective, reducing rather than eliminating current through the deflection coils during the no-data periods. A need therefore exists for a simple, inexpensive technique for completely eliminating current flow through the deflection coils of a display device CRT during periods of each frame when there is no data or raster.

SUMMARY OF THE INVENTION

In accordance with the above this invention provides a circuit for use in a cathode ray tube (CRT) display device of the type having a horizontal deflection coil for controlling the horizontal position of the CRT beam and a vertical deflection coil for controlling the vertical position of the CRT beam, which circuit is operative to substantially eliminate current flow through both of the deflection coils when the beam is not being moved by

the coils through a raster pattern. The circuit includes a time-out means for generating a predetermined signal when the beam is not being moved through the raster pattern. For a preferred embodiment, the time-out means includes a time-out circuit which generates an output at all times except for a predetermined time period after it receives an input. The circuit also includes a means operative when the beam is being moved through a raster pattern for applying successive pulses 10 as inputs to the time-out circuit, the time period between the pulses being less than the predetermined time period. Horizontal and vertical control means are provided for respectively controlling the current flowing through the horizontal and vertical deflection coils. 15 A means is included as part of each of the control means which is responsive to a signal from the time-out means for causing each of the control means to apply substantially zero current to the corresponding deflection coil. For a preferred embodiment of the invention, each of the control means includes a deflection amplifier, a capacitor, the capacitor being connected such that the charge thereacross serves as the control potential applied to the deflection amplifier, a resistor connected to permit the capacitor to discharge to, and be maintained at, a predetermined potential level which, when applied to the corresponding deflection amplifier, results in no current being applied to the corresponding deflection coil, and a means for permitting each capacitor to discharge through the corresponding resistor only when there is a signal from the time-out means.

The foregoing and other objects, features and advantages of the invention will be apparent from the following more particular description of the invention as shown in the accompanying drawings.

BRIEF DESCRIPTION OF DRAWINGS

FIG. 1 is a diagram showing the face of a CRT with an exemplary raster for a preferred embodiment of the invention.

FIG. 2 is a semi-block schematic diagram of a circuit incorporating the teachings of this invention.

FIG. 3 is a timing diagram illustrating the signals appearing at selected points in the circuit of FIG. 2.

DETAILED DESCRIPTION

Referring now to FIG. 1, a cathode ray tube (CRT) screen 10 is shown. It is assumed that each frame of data on this screen occupies nine lines with the raster pattern for each frame starting at point 12 on the screen and ending at point 14. The raster pattern is of the type described in U.S. Pat. No. 3,500,327, entitled "DATA HANDLING APPARATUS" issued Mar. 10, 1970 to Richmond D. Belcher, et al and assigned to the assignee of the present application. With this type of raster, there is a single horizontal sweep of the screen for each line of the display with six or seven vertical strokes being provided for each character to be displayed on the line. Seven index points on each of five strokes for each character are selectively intensified to form a desired character, the remaining one or two strokes of each character being for intercharacter spacing.

Referring now to FIG. 2, a horizontal deflection coil 16 and a vertical deflection coil 18 are provided which coils are normally mounted on the neck of the CRT. When neither of the coils 16 or 18 has current applied

to it, the CRT beam is positioned at approximately the middle of the screen (position 20 shown in FIG. 1). A negative potential applied to coil 16 moves the beam to the left and a positive potential applied to coil 16 moves the beam to the right, the amperage of the current flowing through the coil in each instance determining how far to the left or right the beam is moved. Similarly, a negative potential applied to coil 18 moves the CRT beam up from point 20 and a positive potential applied to coil 18 moves the beam down from point 20, the quantity of current flowing through coil 18 again determining the extent of the movement.

A horizontal scan signal is applied through horizontal scan (HSCN) line 22 to a horizontal scan control circuit 24. More specifically, line 22 is connected through a resistor 26 to the base of a transistor 28. The emitter of the transistor is connected to ground while collector of the transistor is connected through a line 32 and a variable resistor 34 to a source of positive potential. A capacitor 36 is connected between the emitter and collector of transistor 28.

Line 32 is the output from circuit 24 and is connected as one input to horizontal deflection amplifier 38. Amplifier 38 controls the current flow to horizontal deflection coil 16 which is connected to the output of the amplifier. The other side of coil 16 is connected through resistor 40 to ground and is also connected through a feedback circuit 42 as a feedback input to the horizontal deflection amplifier.

Frame return (FR) line 44 and line step line (LNSP) 46 are connected as inputs to vertical control circuit 48. In particular, line 44 is connected through resistor 50 to the base of transistor 52. The emitter of this transistor is connected directly to ground and a capacitor 56 is connected between the emitter and collector of the transistor. The collector of the transistor is also connected through a line 58 and diode string 60 to a constant current source 62. LNSP line 46 is connected through a diode 64 to a point between diode string 60 and the constant current source.

Line 58, which is the output line from circuit 48, is connected as one input to a vertical deflection amplifier 66 which controls the current flow through vertical deflection coil 18. An isolation coil 68 is connected between amplifier 66 and coil 18, the other side of coil 18 being connected through resistor 70 to ground, and through feedback circuit 72 to vertical deflection amplifier 66.

HSCN line 22 is also connected as the input to time-out circuit 74. In particular, line 22 is connected through resistor 75 to the base of transistor 76, the emitter of this transistor being connected to ground and the collector of the transistor being connected through a line 78 and a resistor 80 to a source of positive potential. A capacitor 82 is connected between the emitter and collector of transistor 76. Line 78 is connected through a resistor 84 to the base of a transistor 86. The base of transistor 86 is also connected through a resistor 88 to a source of negative potential, with the emitter of transistor 86 being connected to ground and the collector of the transistor being connected through a line 90 and a resistor 92 to a source of positive potential.

Line 90 is also the output line from time-out circuit 74. Line 90 is connected through a variable resistor 92 and a diode 94 to line 32 of horizontal control circuit 24 and is also connected through variable resistor 96

and diode 98 to line 58 of vertical control circuit 48.

OPERATION

Referring now to FIG. 3, and in particular to line A of this figure, it is seen that the frame period for the illustrative embodiment of the invention is 16.67 milliseconds (i.e., a refresh rate of 60 Hz). However, from lines B and C, it can be seen that the refresh of each line requires only 695 microseconds. Therefore, the nine lines of the display are refreshed in roughly 6.25 milliseconds leaving roughly 10.42 milliseconds millisecond when no raster is being traced on screen 10.

In operation, a frame retrace pulse 100 is first applied to line 44 causing transistor 52 to become conductive for 695 microseconds, a period sufficient for capacitor 56 to be fully discharged through the transistor. At the end of pulse 100, short 73 microsecond pulses 102 and 104 are applied to HSCN line 22 and LNSP line 46 respectively. The signal on line 46 back-biases diode 64, permitting current from constant current source 62 to flow into capacitor 56 through diode string 60. Thus, for the duration of the pulse on line 46, an increment of charge is applied to capacitor 56 raising the potential level on line 58 to the level 106 (FIG. 3E). This positive potential level applied to vertical deflection amplifier 66 results in a negative output current through vertical deflection coil 18 which is of such magnitude as to position the CRT beam for writing on the first line of the display shown in FIG. 1 (i.e., the line for starting point 12).

At the time that the HSCN pulse 102 appears on line 22, time-out circuit 74 is set with transistor 76 cut-off and transistor 86 conducting so that the output on line 90 is at substantially ground potential. The pulse 102 is applied to turn transistor 76 on, permitting the charge on capacitor 82 to leak off therethrough. The discharge of capacitor 82 causes the base of transistor 86 to go negative under the influence of the signal from the minus voltage source through resistor 88. This cuts off transistor 86, resulting in a positive potential being applied to line 90, which back biases both diodes 94 and 98 preventing current from flowing on line 90.

The HSCN pulse 102 is also applied to turn on transistor 28, permitting capacitor 36 to become discharged. The potential on line 32 when capacitor 36 is fully discharged is applied to horizontal deflection amplifier 38, resulting in a negative output current being applied through horizontal deflection coil 16 which is of sufficient magnitude to move the beam to its left-most-position (i.e., the position of starting point 12) on a line.

When pulses 102 and 104 terminate, capacitor 36 starts to charge through resistor 34 and capacitor 82 starts the charge through resistor 80. The charging of capacitor 36 results in a ramp voltage appearing on line 32 (FIG. 3D) which voltage, when applied to horizontal deflection amplifier 38, results in suitable current being applied through horizontal deflection coil 16 to move the CRT beam across a line of the display from starting point 12 to the right-most position in which data is to be displayed. The charging of capacitor 82 increases the potential on line 78 and thus the potential applied to the base of transistor 86. However, the relative values of the voltage sources and of the resistors 84 and 88, and the value of capacitor 82 and thus its charging rate, are such that approximately 1,000 mi-

croseconds (1ms) are required after capacitor 82 has been discharged before the charge on the capacitor is sufficient to cause the base of transistor 86 to go positive turning the transistor on. However, after 695 microseconds, signals again appear on lines 22 and 46, the signal on line 22 again discharging capacitor 82 before it has had a chance to charge sufficiently to turn transistor 86 on. The signal on line 46 causes another increment of charge to be applied to capacitor 56 stepping the beam down to write on the second line of the display (FIG. 1) and the signal on line 22 results in capacitor 36 being discharged in the manner previously indicated, causing the CRT beam to again be returned to its left-most writing position.

When the pulse on line 22 terminates, capacitor 36 again starts charging, causing the CRT beam to scan across the second line of the display. Capacitor 82 also starts charging.

The above-described sequence of operations is repeated for each succeeding line of the display, with increments of charge being applied to capacitor 56 to step the CRT beam down for each succeeding line, capacitor 36 being charged to scan the beam across each line and then discharged by an HSCN pulse on line 22 to return the beam to its left-most writing position, and capacitor 82 being discharged by each HSCN pulse on line 22 before it is charged sufficiently to turn transistor 86 on, resulting in a continuous positive output on line 90 from time-out circuit 74. However, after the ninth HSCN pulse 108 on line 22, there are no further pulses on this line for the remainder of the frame. Thus, one thousand microseconds after the pulse 108 appears on line 22 (a little over 300 microseconds after writing at point 14 of the display) capacitor 82 becomes sufficiently positively charged to cause transistor 86 to become conductive. This results in line 90 going to essentially ground potential, forward biasing both diodes 94 and 96. Diode 94 being forward biased permits capacitor 36 to partially discharge through diode 94, resistor 92, line 90, and transistor 86. The value of resistor 92 is adjusted such that the potential across capacitor 36, and therefore the potential on line 32 is at the proper level to cause horizontal deflection amplifier 38 to apply zero current to horizontal deflection coil 16. This potential is roughly equal to half the potential required to move the beam from the left-most writing position on a line to the right-most writing position on a line, the beam thus being positioned at roughly the midpoint of a line. The potential on line 32 (and therefore the charge across capacitor 36) is maintained by current flow from the source of positive potential through resistor 34, diode 94, resistor 92, etc.

Similarly, capacitor 56 discharges through diode 98, resistor 96, line 90, and transistor 86. The value of resistor 96 is adjusted such that the potential across capacitor 56, and thus on line 58 is at the proper level to cause vertical deflection amplifier 66 to apply zero current to vertical deflection coil 18. This potential is roughly half the potential required to move the beam from top to bottom of screen 10, the residual charge remaining on capacitor 56 thus causing the potential on line 58 to be such as to cause deflection amplifier 66 to pass zero current through coil 18 to position the beam at roughly the vertical position of point 20. This potential on line 58 (and thus across capacitor 56) is maintained by current flow from constant current

source 62, through diode string 60, diode 98, resistor 96, etc.

Thus, so long as line 90 is at ground potential (i.e., so long as time-out circuit 74 is in a time-out condition), there is zero current flowing through both horizontal deflection coil 16 and vertical deflection coil 18. There is also zero current flowing in isolation coil 68 and in the other output elements of the circuit (some of which are not shown). This zero-current condition in the deflection coils exists for roughly 10 ms of each 16.67 ms frame period, or, in other words, for roughly 60 percent of each frame period. Circuit and component heating and element wear are thus significantly reduced resulting in significantly improved reliability and 15 significantly lower maintenance.

While the invention has been described above with respect to a multi-line stroke raster scan, it is apparent that the invention is equally applicable with other raster scanning techniques. All that is required is that 20 there be a sync pulse signal which appears only when raster is being generated, the absence of this signal then being used to permit a time-out circuit to time-out, and the outputs from the time-out circuit being utilized to control the current applied to the deflection amplifiers such that zero current is applied to the amplifiers. Thus, while the invention has been particularly shown and described above with reference to a preferred embodiment, it will be understood by those skilled in the art that the foregoing and other changes in form and 25 detail may be made therein without departing from the spirit and scope of the invention.

What is claimed is:

1. In a cathode ray tube (CRT) display device of the type having a horizontal deflection coil for controlling the horizontal position of the CRT beam, a vertical deflection coil for controlling the vertical position of the CRT beam, and horizontal and vertical control means for respectively controlling the current flowing through said horizontal and vertical deflection coils, said coils being operative under control of said control means for moving the beam through a selected raster pattern, a circuit for substantially eliminating current flow through both of said deflection coils when the beam is not being moved through said raster pattern, comprising:

a time-out circuit which generates a selected output at all time except for a predetermined time period after it receives an input;

means operative when the beam is being moved through a raster pattern for applying successive pulses as inputs to said time-out circuit, the time period between said pulses being less than said predetermined time period; and

means included as part of each of said control means and responsive to the selected output from said time-out circuit for causing each of the control means to apply substantially zero current to the corresponding deflection coil.

2. A circuit as claimed in claim 1 wherein said horizontal control means include a horizontal deflection amplifier and a horizontal scan control circuit connected to selectively apply voltage variable signals to the deflection amplifier to move the beam horizontally across the CRT; and

wherein said successive pulses are horizontal scan control pulses which are also applied to reset said horizontal scan control circuit.

3. A circuit as claimed in claim 2 wherein said horizontal scan control circuit includes a capacitor which, when charged to a predetermined potential level, causes an input to be applied to said horizontal deflection amplifier which results in no current being applied to the deflection coil, a current of a first polarity being applied to the deflection coil to move the beam in a first direction when the capacitor charged to a level less than said predetermined potential level and a current of a second polarity being applied to the deflection coil to move the beam in the opposite direction when the capacitor is charged to a level greater than said predetermined level; and

wherein said horizontal control means includes a resistor connected to permit said capacitor to discharge therethrough to said predetermined potential level when said time-out circuit generates said selected output.

4. A circuit as claimed in claim 3 wherein said horizontal control means includes a diode connected to permit said capacitor to discharge through said resistor only when there is said selected output from said time-out circuit.

5. A circuit as claimed in claim 1 wherein said horizontal control means includes a horizontal deflection amplifier, a capacitor, the capacitor being connected such that the charge thereacross serves as the control potential applied to the deflection amplifier, and a resistor connected to permit said capacitor to discharge therethrough to a predetermined potential level which when applied to the horizontal deflection amplifier, results in no current being applied to the horizontal deflection coil, and means for permitting said capacitor to discharge through said resistor only when there is said selected output from said time-out circuit.

6. A circuit as claimed in claim 5 wherein said means for permitting said capacitor to discharge includes a diode connected between said capacitor and said resistor.

7. A circuit as claimed in claim 1 wherein said vertical control means includes a vertical deflection amplifier, a capacitor, the capacitor being connected such that the charge thereacross serves as the control potential applied to the deflection amplifier, a resistor connected to permit said capacitor to discharge therethrough to a predetermined potential level which, when applied to the vertical deflection amplifier, results in no current being applied to the vertical deflection coil, and means for permitting said capacitor to discharge through said resistor only when there is said selected output from said time-out circuit.

8. A circuit as claimed in claim 7 wherein said means for permitting said capacitor to discharge includes a diode connected between said capacitor and said resistor.

9. A device as claimed in claim 1 wherein said horizontal and said vertical control means each includes a deflection amplifier, a capacitor, the capacitor being

connected such that the charge thereacross serves as the control potential applied to the corresponding deflection amplifier, a resistor connected to permit the corresponding capacitor to discharge therethrough to a predetermined potential level which, when applied to the corresponding deflection amplifier, results in no current being applied to the corresponding deflection coil, and means for permitting each of said capacitors to discharge through the corresponding resistor only when there is said selected output from said time-out circuit.

10. A device as claimed in claim 9 wherein each of said means for permitting said capacitor to discharge includes a diode connected between the corresponding capacitor and the corresponding resistor.

11. In a cathode ray tube (CRT) display device of the type having a horizontal deflection coil for controlling the horizontal position of the CRT beam, and a vertical deflection coil for controlling the vertical position of the CRT beam, said coils being operative when suitably energized for moving the beam through a selected raster pattern, a circuit for substantially eliminating current flow through both of said deflection coils when the beam is not being moved through said raster pattern, comprising:

time-out means operative for generating a selected output when the beam is not being moved through said raster pattern; and

horizontal and vertical control means for respectively controlling the current flowing through said horizontal and vertical deflection coils, said horizontal and vertical control means each including a deflection amplifier, a capacitor, the capacitor being connected such that the charge thereacross serves as the control potential applied to the corresponding deflection amplifier, a resistor connected to permit said capacitor to discharge therethrough to a predetermined potential level which, when applied to the corresponding deflection amplifier, results in no current being applied to the corresponding deflection coil, and means for permitting each of said capacitors to discharge through the corresponding resistor only when there is said selected output from said time-out means.

12. A device as claimed in claim 11 wherein each of said means for permitting said capacitor to discharge includes a diode connected between the capacitor and the corresponding resistor.

13. A device as claimed in claim 11 wherein said time-out means includes a time-out circuit which generates the selected output at all times except for a predetermined time period after it receives an input;

and including means operative when the beam is being moved through a raster pattern for applying successive pulses as inputs to said time-out circuit, the time period between said pulse being less than said predetermined time period.
